UNITED STATES PATENT OFFICE.

LUCIEN I. YEOMANS, OF CHICAGO, ILLINOIS, ASSIGNOR TO AMALGAMATED MACHINERY CORPORATION, OF CHICAGO, ILLINOIS, A CORPORATION OF DELAWARE.

PLANEER.

1,309,384.

Specification of Letters Patent.

Patented July 8, 1919.

Application filed March 30, 1918. Serial No. 225,637.

To all whom it may concern:

Be it known that I, LUCIEN I. YEOMANS, a citizen of the United States, residing at Chicago, in the county of Cook and State of Illinois, have invented certain new and useful Improvements in Planers, of which the following is a specification.

Planers have heretofore been constructed of metal. If the long bed of a large-size planer were anchored to the foundation throughout its entire length or at various points along its length, the force due to expansion caused by temperature changes would be practically irresistible and the alinement of the bed would be destroyed by yield at the weakest point. It is, therefore, common practice to anchor the bed to the foundation only at the housings, thus leaving both ends of the bed free to expand lengthwise. While this arrangement obviates the distortion due to the difference in the coefficients of expansion of the masonry foundation and the metal planer bed, expansion will still cause more or less irregular distortion of the planer bed and throw it out of alinement, since the casting or castings constituting the planer bed are more in tension at certain points than at others on account of the usual internal casting strains, these strains being differently relieved by the expansion.

It will be seen that the difficulties in preserving alinement of the bed, due to expansion and contraction of the materials of which planers have been constructed, have limited the practicable size of planers.

One of the objects of this invention is to provide a system of construction which shall not be subject to the limitations which we have seen to inhere in previous forms, and whereby machines for planing metal may be built of any desired size.

Another object of the invention is to provide a system of constructing machines for planing metal whereby such machines may be built comparatively quickly and cheaply. Heretofore such planers have comprised large metallic parts, the casting and machining of which involved the expenditure of much time and money. In fact, one of the great difficulties in speeding up the production of metallic parts of maximum size (as, for example, the large-size beds of ammunition lathes and other large metallic parts

entering into the construction of munitions 55 of war) has been largely due to the lack of machine tools of the necessary capacity. Such limitations upon production are particularly deplorable in the case of munitions of war or of large machine tools used in the 60 production of munitions.

The first-mentioned object is attained by constructing the planer bed of material having a much higher specific heat than iron, thus greatly reducing expansion and contraction due to temperature changes; and by providing the bed with metallic wearing surfaces formed on comparatively short metal sections rigidly anchored to the bed, spaces to permit expansion being left between adjacent sections.

The second-mentioned object may be attained by constructing the bed, housings and cross-beam as a massive monolith of reinforced concrete.

The invention also relates to the further improvements in planers hereinafter set forth.

In the accompanying drawings, Figure 1 is a side elevation of a planer embodying 80 the features of my invention. Fig. 2 is a top plan view of the planer. Fig. 3 is a fragmental side elevation on a larger scale. Fig. 4 is an end elevation. Fig. 5 is a fragmental horizontal section through the bed 85 of the planer. Fig. 6 is a detail view showing the means for anchoring and attaching the ways. Fig. 7 is a view showing the means for reversing the direction of travel of the platen. Fig. 7^a is a section on line 90 a—a of Fig. 7. Fig. 8 is a fragmental vertical sectional view of the planer, taken on line 8—8 of Fig. 3. Fig. 9 is a fragmental top plan view of the platen with the concrete omitted. Fig. 10 is a fragmental side 95 elevation of the platen and the ways upon which it is mounted. Fig. 11 is a plan view of one of the way sections. Fig. 12 is a fragmental view of the platen upon an enlarged scale, showing also the means for reciprocating the platen. Fig. 13 is a transverse sectional view of the platen and the ways. Fig. 14 is a transverse sectional view of the bed, the ways, and the platen, taken in the plane of dotted line 14—14 of Fig. 18. 100 Fig. 15 is a fragmental longitudinal sectional view of the platen and its ways. Fig. 16 is a detail view of one of the features of

construction of the platen. Fig. 17 is a section on line 17—17 of Fig. 12. Fig. 18 is a fragmental horizontal sectional view through the bed showing the means for reciprocating the platen. Fig. 19 is a diagram of the belt-shifting means. Fig. 20 is a fragmental end elevation of the housing, showing the head rail and one of the tool carriages mounted thereon. Fig. 21 is a vertical sectional view of parts shown in Fig. 20, the view being taken in the plane of line 21—21 of Fig. 4. Fig. 22 is a section taken approximately on dotted line 22—22 of Fig. 4.

15 For the purpose of imparting an understanding of the invention, I have selected for illustration a planer which has been constructed in accordance with the invention and having a bed 184 feet long, said planer 20 being capable of planing a casting 90 feet long.

For convenience in handling the work, a machine embodying the invention is preferably constructed so that the bed is approximately flush with the floor. When so located, the first step in the process of constructing the machine consists in excavating a trench of suitable depth, length and width. In this trench is poured a concrete 30 footing 1. After the footing has set, suitable forms are erected for the bed 2, the housings 3 and the beam 4. Within these forms are placed metal reinforcing bars 5, said bars being secured in place in any well-known or suitable manner so as not to be disturbed during the pouring of the concrete. The bars 5 reinforce the beam 4 against all tensional and torsional stresses that may arise in use. The bed 2 and the 40 housings 3 are made so massive that the concrete alone would bear all stresses arising in the operation of the planer. However, the bed and the housings are heavily reinforced by bars 5 against the stresses arising 45 in the shrinkage of the concrete and in the expansion and contraction due to temperature changes. Sufficient reinforcing is employed to prevent such stresses from resulting in isolated cracks of serious character, 50 the stresses being so distributed by the reinforcing bars that such cracks as may form are widely distributed and exceedingly small, and hence of no consequence.

At opposite sides of the housings 3 the 55 bed is widened as indicated at 1^a.

The platen 6 is mounted upon metallic ways rigidly secured from one end to the other to the bed 2. As shown in Figs. 1, 2, 10, 11, 13 and 14, the ways 60 consist of a plurality of transverse sections 7 rigidly secured to the bed and spaced apart from one another sufficiently to allow each to expand with a rise in temperature without coming in contact with adjacent sections. The sections 7 are compara-

tively short so that any expansion that may occur will be very slight. Each section comprises a flat rail 8 and a V-grooved rail 9 rigidly secured together by means of transverse webs 10. In each section 7 there are several longitudinally elongated holes 11 (Figs. 6 and 11) formed along both sides of each of the ways 8 and 9 to receive anchor bolts 12 (Figs. 6 and 13) embedded in the bed 2. Nuts 13 screwed upon the upper ends of the anchor bolts 12 serve to hold the sections 7 down in the desired plane. Vertical adjusting screws 14 are screwed into holes 14^a (Fig. 11) in the sections 7 at various points along each side of each of the rails 8 and 9 and bear against the top of the bed 2. By means of the nuts 13 and screws 14, the way-sections 7 are accurately adjusted with reference to the true level, as distinguished from the apparent level.

Upon the lower face of each section 7 are cast a number of downwardly-extending lugs 15 (Figs. 15 and 17), there being a plurality of such lugs at each side of the median line of each section. These lugs project downwardly into recesses 16 formed in the bed 2. Internally-threaded bushings or sleeves 17 (Fig. 17) are embedded in the bed 2 in a horizontal position for the reception of adjusting screws 18 arranged to bear 95 against the opposing faces of the lugs 15.

By means of the screws 18 the sections 7 are adjusted into alinement with each other with reference to a vertical plane. The openings 11 through which the anchor 100 bolts 12 extend are large enough to allow the way sections to move laterally as the screws 18 are adjusted.

During the first two weeks after pouring, concrete shrinks about one-eighth of an inch 105 per foot. Although the concrete continues to harden for an indefinitely long time, the amount of shrinkage after the first two weeks is negligible for practical purposes. After shrinkage of the bed 2 has practically 110 ceased, the sections 7 of the ways are placed upon the bed and the nuts 13 and the screws 14 and 18 adjusted until the sections of the rails 8 and 9 are perfectly alined. A concrete grout 19 is then poured between 115 the bed and the sections 7 to make the ways substantially integral with the bed.

The platen 6 is constructed of reinforced concrete. The reinforcing consists partly of bars and partly of castings. The castings serve also to provide skids that slide upon the rails 8 and 9. Said castings also provide undercut slots in the upper surface of the platen for the reception of the bolts used to attach the work to the platen. 125 Each of said castings (which will be hereinafter termed platen sections 20) is of hollow box-like form. Upon the lower side of each platen section is a flat skid 21 (Fig. 13) arranged to slide upon the rail 8 and a V- 130

shaped skid 22 adapted to slide in the grooved rail 9. In the upper side of each platen section is a suitable number of undercut longitudinal grooves 23 for the reception of the work-attaching appliances. Each section 20 comprises a plurality of transverse webs 24 (Fig. 15) having openings 25 (Figs. 15 and 17) therein through which reinforcing bars 26 are passed and 10 through which the concrete 27 flows. Reinforcing bars 26 also lie in notches 28 formed in the upper edges of the transverse webs 24. The bars 26 are preferably of materially greater length than the platen 15 sections so as to extend through a plurality of adjacent sections, the ends of the bars being preferably hooked or bent as shown in Fig. 15. The end portions of the bars in any given row are overlapped to a substantial extent as represented in Fig. 15, the laps in the different rows being staggered.

In order to prevent such sand or grit as may form through granulation of the concrete of the platen from falling on the rails 8 and 9, sand-proof joints are provided between adjacent platen sections. While such joints may be constructed in various ways, the form herein shown comprises a tongue 29 (Figs. 16 and 17) formed upon the end of one section and overlying a flange 30 on the adjacent end of the adjacent section. Before the concrete is poured, a strip of suitable material, as, for example, canvas 31, is inserted into the space between the tongue 29 and the flange 30 so as to constitute virtually a lining for said space. The space is then calked with oakum 32 or the like, after which the concrete is poured into 40 the platen sections. The canvas 31 and oakum 32 prevents any grit from falling through the space between adjacent platen sections and onto the rails 8 and 9.

Preferably the joints just described do not 45 extend straight across the sections, but are of angular form as indicated in Fig. 9. As shown in said figure, the platen sections that form the opposite ends of the platen have square or plain outer ends. The inner 50 ends of the head section and the tail section are formed to provide sand-proof joints with the adjacent ends of the intermediate sections.

The rails 8 and 9 are lubricated by means 55 of rolls 33 (Fig. 13) mounted within oil pockets 34 in the way-sections 7. Said rolls have peripheries suitably formed to make contact with the skids 21 and 22 as the platen reciprocates upon its ways. In their 60 rotation, the rolls 33 carry up oil to the skids, from whence the oil is carried onto the rails 8 and 9. If desired, the peripheries of the rolls 33 may be grooved, as shown, for greater effectiveness in carrying oil. 65 The rolls are mounted on plates 35 which are

supported on expansion springs 36, whereby the rolls are yieldingly pressed against the skids 21 and 22.

The platen is reciprocated by means of a spur-gear or "bull-wheel" meshing with a 70 rack 37 secured to the lower side of the platen. Said rack is formed in sections which are attached to the platen by means of bolts 38 (Fig. 13) that extend through longitudinally elongated holes 39 in the rack 75 sections and through holes 40 in the platen sections. On each rack section is a locating rib 41 that fits into a groove 42 in the lower side of the platen.

The method of assembling the platen is 80 as follows: The platen sections 20 are laid up-side-down upon a floor or other plane surface and arranged in alignment with suitable spaces therebetween for the sand-proof joints. The rack sections are 85 then secured to the platen sections by means of the bolts 38. If desired, the end sections of the rack may be further secured to the end platen sections by means of dowel pins 43 (Fig. 9). As indicated in Fig. 12, the 90 rack sections break joints with the platen sections. The correct spacing of the rack teeth on the adjacent ends of the rack sections is obtained by planing off more or less of the chipping pads 44 (Fig. 17) provided 95 on the ends of the rack sections. After the entire rack has been attached to the platen sections, those rack sections that overlap adjacent platen sections are removed, thus disconnecting the platen sections from each 100 other. The rails 8 and 9 having been greased, the platen sections are transported to and placed in proper order upon said rails. The rack sections that overlap adjacent platen sections are then secured in 105 place, thus uniting all of the platen sections.

The workmen gain access to the lower sides of the platen sections through the passageway 45 (Figs. 14 and 18) extending longitudinally of the bed, and through the 110 open spaces 46 (Fig. 11) in the way-sections 7. The sand-proof joints between the platen sections are then made; the reinforcing bars 26 are set in place; and the platen sections are filled with concrete. 115

The bull-wheel 47 (Figs. 12, 17 and 18) is fixed upon a shaft 48 which is mounted in bearings 49. The bull wheel is driven through a reduction gear train formed of the gear wheels 50, 51, 52, 53, 54, 55, 56, 57 120 and 58. The bearings 49 and the bearings for the shafts that carry the reduction gears are secured to the bed by means of anchor bolts 59 (Fig. 3). After the platen has been constructed, the bearings 49 for the 125 bull-wheel shaft 48 are set and adjusted so that the bull-wheel meshes properly with the rack 37. The bearings for the shaft that carries the pinion 50 are then properly positioned. The end bearings for the re- 130

maining shafts are formed in sets for convenience in locating and securing said bearings in place. After the various shaft bearings have been properly fixed in position, 5 grout is placed between the bearings and the bed, as indicated, for example, at 60 in Fig. 3.

The shaft 61 that carries the pinion 58 is arranged to be driven alternatively in opposite directions by means of two electric 10 motors 62 and 63 mounted on the bed (see Fig. 18). The motors are belted to pulleys 64 and 65 carried by shafts 66 and 67. On each of said shafts is a wide pulley 68. Belts 15 69 and 70 extend from the pulleys 68 to tight pulleys 71 and 72 and loose pulleys 73 and 74 on the shaft 61. In operation, the motors run constantly, the belts 69 and 70 being alternately shifted onto their respective 20 tight pulleys.

Any suitable means may be employed to shift the belts 69 and 70. Herein are shown pressure-fluid-actuated belt shifter loops 75, each connected to the piston of a compressed-air cylinder, the cylinders being indicated at 76 and 77.

The supply of pressure-fluid to the opposite ends of the cylinders is controlled by means of valve mechanism of suitable construction. The arrangement employed in the present embodiment will be best understood by referring to Fig. 19. 78 is a compressed air supply pipe leading to a four-way cock 79. The oscillatory valve member 30 80 has a port 81 therein adapted to connect the supply pipe 78 with a pipe 82 that extends to a three-way cock 83. The oscillatory valve member 84 of the three-way cock 83 is adapted to connect the pipe 82 with a pipe 85 leading to one end of the cylinder 76. At the same time, the valve member 84 connects the pipe 82 with a pipe 86 leading to the corresponding end of the cylinder 77. The valve member 80 of the four-way cock 35 79 has a port 87. When the port 81 connects the pipes 78 and 82, the port 87 connects an exhaust pipe 88 with a pipe 89 that extends to a three-way cock 90. The valve member 91 of the cock 90 has a passage adapted to 40 connect the pipe 89 with a pipe 92 that leads to the end of the cylinder 76 opposite to the end supplied by the pipe 85. At the same time, the valve member 91 connects the pipe 89 with a pipe 93 that leads to the corresponding end of the cylinder 77. The valve member 80 is oscillated so as to connect the pipes 82 and 89 alternately with the feed pipe 78 by suitable means, such as that shown, for example, in Fig. 7. 94 is a bar 45 fixed to the platen and extending longitudinally thereof. Valve-tripping devices are adjustably mounted upon the bar 94 at points determining the length of travel of the platen. When the platen is completing 60 a feed movement, the tripping device 95

strikes a finger 96 adjustably mounted upon an arm 97, said arm being rigid with the valve member 80, thus turning said valve member into position to connect the supply pipe 78 with the pipe 89 and to connect the 70 pipe 82 with the exhaust pipe 88. The pistons in the cylinder 76 and 77 are thereby moved to cause the belts 69 and 70 to be shifted onto the loose pulley 73 and the tight pulley 72, respectively. The shaft 61 will 75 then be driven at relatively high speed to return the platen to initial position. As the platen approaches its initial position, a tripping block 98 on the bar 94 strikes the finger 96 and moves said finger into the dotted-line 80 position shown in Fig. 7, thus turning the valve member 80 into the position shown in Fig. 19, and causing a shifting of the belts 69 and 70 to the tight pulley 71 and the loose pulley 74, respectively. Another feed stroke 85 will thereupon be imparted to the platen.

In order to provide means for stopping the platen at any time, the following described means is employed: A four-way cock 99 (Fig. 19) is connected to the supply pipe 90 78 by means of a pipe 100. Said valve also is connected to the pipe 92 by means of the pipes 101 and 102. The pipe 101 is connected to the pipe 86 by means of a pipe 103. Check valves 104 and 105 are connected into the pipes 102 and 103, respectively. The four-way cock 99 is connected to the pipe 85 by means of the pipes 106 and 107. The pipe 106 is connected to the pipe 93 by means of a pipe 108. Check valves 109 10 and 110 are located in the pipes 107 and 108, respectively. 111 is an exhaust pipe. The oscillatory valve member 112 of the cock 99 has two ports 113 and 114. The valve member 112 may be manually operated in any 10 suitable manner. Herein is shown a vertical rock shaft 115, the lower end of which is provided with a socket 116 that fits upon the stem (not shown) of the valve member 112. Hand levers may be placed upon the rock 11 shaft 115 at any convenient points. Herein are shown a hand lever 117 accessible to a workman standing beside the bed and a hand lever 118 for operation by a workman standing upon the beam 4. The valve members 11 84 and 91 are connected to the rock shaft 115 by suitable means, as, for example, the crank arms 119 and 120 and the links 121.

Fig. 19 shows the parts arranged to produce a feed stroke of the platen. If it be 12 desired to stop the platen, the rock shaft 115 is turned so as to move the valve members 84 and 91 through an arc of about 45 degrees, thereby blanking all of the ports in the three-way valves 83 and 90. The same movement of the rock shaft 115 turns the valve member 112 so as to place the port 113 in communication with the feed pipe 100 and the pipe 101 and to place the port 114 in communication with the pipes 106 and 111. 13

Compressed air will then flow from the pipe 100, through the port 113, through the pipe 101, past the check valve 104, through the pipes 102 and 92, into one end of the cylinder 76, causing the piston in said cylinder to move to place the belt 69 on the loose pulley 73. Air exhausts from the other end of the cylinder 76, through the pipes 85 and 107, past the check valve 109, and through the pipe 106 and the port 114, to the exhaust pipe 111. In this operation, the cylinder 77 has not been affected, since the end of said cylinder which was under pressure is still under pressure through the pipes 101, 103 and 86; and the end of the cylinder 77 which was open to the exhaust is still connected to the atmosphere through the pipes 93, 108 and 106. When it is desired to again set the platen in motion, the shaft 115 is operated to restore the three-way cocks 83 and 90 and the four-way cock 99 to the position shown in Fig. 19, whereupon the piston in the cylinder 76 will be moved to place the belt 69 upon the tight pulley 71.

When a return stroke is being imparted to the platen, the platen may be stopped and restarted by operating the rock shaft 115 to blank the three-way cocks 83 and 90 and set the four-way cock 99 in the position hereinbefore described. The cylinder 77 will then be operated, while the cylinder 76 remains inactive.

Any suitable means may be provided for supporting the tools. Herein is shown a head rail 122 (Fig. 20), said rail comprising a web that covers the forward face of the beam 4, a longitudinal flange 123 that overlies said beam, and a longitudinal flange 124 that underlies the beam. The head rail 122 is rigidly secured to the beam 4 by means including bolts 125 which extend through openings 126 provided in any suitable manner in the beam 4 (see Fig. 8). The bolts 125 extend through the beam 4 and the head rail 122. The head rail 122 is accurately located in position and fixed upon the beam 4 by means of vertical adjusting screws 127 extending through the flanges 123 and 124 and bearing against the upper and lower sides of the beam 4. After the head rail 122 has been secured in place by means of the bolts 125 and the adjusting screws 127, the space between the head rail and the beam 4 is filled with grout, as indicated at 128.

Upon the head rail 122 is a horizontal guide 129 upon which a suitable number of tool heads 130 may be slidably mounted. Two such heads are herein shown. Said heads may be adjusted by any preferred means, as, for example, a screw 131 extending longitudinally of and fixed to the head rail 122. Each head 130 is provided with a nut 132 (Fig. 22) fitting upon the screw 131 and arranged to be rotated by means in-

cluding a hand wheel 133 located within convenient reach of a workman standing upon the beam 4. The tools (not shown) are carried by vertically movable slides 134 on the heads 130, said slides being movable by means of hand wheels 135 which are accessible to an operator stationed on the beam 4.

The form of planer construction herein disclosed renders possible the building of planers of any desired dimensions. The metallic wearing surfaces on the bed are formed upon comparatively short, independently-supported members, hence the very slight changes in length of the various members, due to temperature changes, have no cumulative effect upon the bed as a whole, and consequently the alinement of the bed is not destroyed. Being constructed of material having a high specific heat, the bed is not subject to troublesome expansion and contraction.

It will be apparent that a planer which may fairly be termed of enormous proportions may be constructed in a small fraction of the time required to build a very much smaller planer of metal, since the erection of the formwork for the concrete, the placing of the reinforcement and the pouring of the concrete may be carried out by comparatively unskilled labor, and sufficient men may be placed upon the job to insure completion of the concrete work with any required degree of expedition. Those portions of the planer requiring machine-tool operations consist of comparatively small parts which can be conveniently cast and expeditiously machined on existing machine tools of moderate capacity. While the construction of a large planer according to prior methods may require perhaps two years, the construction of a much larger planer in accordance with the present invention may be completed in a tenth of that time, and at a much lower cost.

I claim as my invention:

1. A planer having, in combination, a bed, housings, and a head-beam, all of monolithic reinforced concrete, and a platen reciprocable on the bed.

2. A planer having, in combination, a monolithic reinforced-concrete bed, a series of way sections rigidly secured to the bed in alinement with each other and spaced apart to permit independent expansion and contraction of said sections, and a platen slidably mounted on the way sections.

3. A planer having a structure, a series of way sections spaced apart from each other to permit independent expansion and contraction of the way sections, means for securing all of said sections to said structure in alinement with each other, and a platen slidably mounted on the way sections.

4. A planer having, in combination, a concrete bed having anchor bolts embedded in

therein, a series of way sections having openings through which said bolts extend, nuts on the bolts above the way sections, adjusting screws carried by the way sections and bearing against the bed, said screws and nuts serving to secure the way sections rigidly to the bed in alinement with each other with reference to a level, and means for adjusting the way sections upon, and securing them to the bed, in alinement with each other with reference to a vertical plane.

5. A planer having a bed provided with a longitudinal passageway, a series of way sections on the bed, means for adjusting 15 said way sections upon the bed and securing them to the bed with reference to a level, lugs projecting downwardly from said way sections at opposite sides of said passageway, and horizontal screws carried by the 20 bed and accessible in said passageway, said screws bearing against said lugs and serving to aline the way sections with reference to a vertical plane.

6. A planer having a bed, a series of way 25 sections secured to the bed in alinement with each other, each way section comprising two rail sections and transverse webs joining said rail sections, openings being provided between said transverse webs, a platen having 30 skids arranged to slide upon said rail sections, a rack secured to the lower side of said platen, a gear wheel carried by the bed and meshing with said rack, and means for driving said gear wheel, a longitudinal passageway being formed in the bed between 35 the rails to afford access to the rack in conjunction with the openings between said transverse webs.

7. A planer having a bed and a platen, 40 said platen consisting of reinforced concrete and including a series of metallic members upon its lower side to provide wearing surfaces to slide on the bed, and sand-proof joints between adjacent members.

45 8. A planer having a bed and a platen, said platen consisting of a series of metal box-like sections, each having a skid on its lower surface to slide on the bed, reinforcing elements extending longitudinally 50 through said series of sections, and concrete filling said box-like sections and investing said elements.

9. A planer having a bed provided with a way and a platen, said platen consisting 55 of a series of metal box-like sections, each having a skid on its lower surface to slide

on the way, and a bolt-receiving groove in its upper surface, reinforcing bars extending longitudinally through said series of sections, said bars being of greater length 60 than the sections, and concrete filling said box-like sections and investing said bars.

10. A planer having a bed provided with a way, a platen consisting of a series of metal box-like sections, each having a skid 65 on its lower surface to slide on the way, reinforcing elements extending longitudinally through said series of sections, each element extending through a plurality of said sections, concrete filling said box-like sections 70 and investing said reinforcing elements, and a rack secured to and extending longitudinally of the lower side of the platen, said rack consisting of sections differing in length from the box-like sections, certain of 75 said rack sections overlapping the ends of adjacent box-like sections.

11. A planer having, in combination, a platen, two elements for driving the platen in opposite directions, two double-acting 80 pressure-fluid cylinders and connections for controlling said elements, a valve controlling the supply of pressure fluid to the ends of said cylinders, means connected to the platen for operating said valve, two intermediate 85 valves each for controlling communication between the first-mentioned valve and one of said cylinders, a valve and connections for by-passing pressure fluid and exhaust fluid around the first-mentioned valve, and 90 means for operating said intermediate valves and said by-pass valve.

12. A planer having, in combination, a platen, two elements for driving the platen in opposite directions, two double-acting 95 pressure-fluid cylinders and connections for controlling said elements, a valve controlling the supply of pressure fluid to the ends of said cylinders, means for automatically operating said valve, two intermediate 100 valves each for controlling communication between the first-mentioned valve and one of said cylinders, a valve and connections for by-passing pressure fluid and exhaust fluid around the first-mentioned valve, and 105 manual means for simultaneously operating said intermediate valves and said by-pass valve.

In testimony whereof I have hereunto set my hand.

LUCIEN I. YEOMANS.
